BALANCED LOOM OPERATION

Frederick D. Snyder, Milton, Mass., assignor to
Westinghouse Electric Corporation, East Pitts-
burgh, Pa., a corporation of Pennsylvania

Application April 4, 1947, Serial No. 739,414

7 Claims. (Cl. 318—74)

1

My invention relates to motor control systems and more particularly to systems of control for correlating the operation of a plurality of electric motors.

In many fields of industry, electric motors operate loads that have the characteristics of a greatly unbalanced flywheel. This is especially true in the textile industry. Usually a large number of looms are mounted on a single floor and each loom is operated by its own motor. If all the looms, or a great number of them, happen to get in step, as happens from time to time, then the sum of all the unbalanced flywheel type loads is transmitted to the floor with the result that the building begins to oscillate. Usually buildings are not designed for such effects, but even if the building were designed for earthquakes, a quaking building does not appear to be a secure place to the personnel.

One broad object of my invention is to so correlate the operation of a plurality of motors, operating loads of the unbalanced flywheel type, that large vibrating stresses are not transmitted to the building.

A more specific object of my invention is to correlate the operation of a plurality of motors disposed on a single floor of a building into pairs such that the two motors comprising each pair are operated out-of-phase to thus balance the individual unbalanced loads in two's.

A somewhat broader object of my invention is the provision of operating two electric motors that an unbalanced load operated by one motor is always substantially 180° out-of-phase with the unbalanced load operated by the other motor.

Other objects and advantages will become more apparent from a study of this specification and the accompanying drawing, in which:

The single figure is a diagrammatic showing of my invention.

In the figure, two looms, 1 and 2, are illustrated graphically. Loom 1 has a crankshaft 3 with a crank 5 which crank is connected to the lever 7 of the lay by the link 9. The lever 7 of the lay is pivoted at 11. A motor M1 rotates the crankshaft 3 through a reduction gear, not shown, so as to oscillate the lever 7 back and forth at speeds such that the lever operating the lay makes from 120 to 220 complete cycles per minute, depending on the motor speed selected. Since the lay weighs a considerable amount, an appreciable vibratory force is set up in the floor supporting the loom. For various reasons, it is not feasible to counterbalance this crankshaft and load.

2

In the figure, 2 represents a second loom. This loom is similar to the first, having the crankshaft 4, crank arm 6, link 10, and the lever 8 for the lay pivoted at 12. The second loom is operated by motor M2. Normally the loom loads are about the same. The looms are driven by individual motors of the same frame size and capacity and are usually adjusted to operate at the same speed.

If a considerable number of the looms or, as may sometimes happen, all of the looms on the same floor happen to get into step, the total force transmitted to the supports becomes great enough to set up dangerous vibrations of the building. One of the purposes of my invention is thus to operate the looms in pairs, and to operate each pair such that the crankshaft of one loom is always out-of-phase with the crankshaft of the other. The out-of-phase relation may be such that one crankshaft is from 160° to 200° behind the other. To break up the unbalance effect of the picker stick, the extreme values are preferable. In this manner, the forces of the two looms that operate as a pair neutralize each other. It thus makes little difference how the pairs operate with respect to each other since no concentrated force will be transmitted to the building floor. How I accomplish the novel result will become more apparent from the detailed description given hereinafter.

The starting and stopping of any two looms that are correlated, that is, combined during normal operation need not be interrelated. If loom 1 is to be started, the attendant actuates controller C1, whereupon the motor M1 is energized from buses L, through controller C1, the lead 13, contacts 15 and lead 17, the lead 19, contacts 21, and lead 23, and lead 25. Energization of leads 23 and 25 energizes the relay 27 to effect the closing of contacts 29.

If loom 2 is to be started, the controller C2 is actuated, whereupon circuits are established from buses L, through controller C2, the lead 14, contacts 16 and lead 18, the lead 20, contacts 22, contacts 22, and lead 24, and lead 26 to energized motor M2. The energization of leads 24 and 26 effects the energization of relay 28 to effect the closing of contacts 30. In the absence of the energization of the control circuits, the two looms 1 and 2 operate independently of each other exactly as is now the case with prior art practice.

To combine the operation of the two looms, I mount two cams 31 and 33 on the crankshaft 3. The cams act on limit switches 35 and 37, respectively. A similar pair of cams 32 and 34 are

mounted on shaft 4. These two cams act on limit switches 36 and 38, respectively.

To gain an understanding of the sequence of operation of the limit switches 35, 36, 37 and 38, I take the trailing edge of the raised portion 39 on cam 31 as the starting point and count angular measure in the clockwise direction, the direction of rotation of the shafts 3 and 4; for the moment consider that the shafts are so disposed that the crank arms 5 and 6 are exactly 180° out of phase.

The raised portion 39 extends from 0° to 60° over the surface of the cam 31. The cam 33 has a raised portion 45 whose trailing edge begins at 10° and extends over the cam surface to 120°. The raised portion 40 on cam 32 extends from its trailing edge in the clockwise direction from 180° to 240°. The raised portion 46 on cam 34 extends from 190° to 300°.

This means for a 60° rotation, contacts 41 are closed and for the remaining 300° contacts 43 are closed, and at the same time, still assuming exact 180° out-of-phase operation of the two crank arms 5 and 6, contacts 42 will be closed for the same 60° rotation; and then contacts 44 will be closed for the remaining 300° rotation. This also means that contacts 47 are closed for 110° beginning 60° ahead of the closure of contacts 41 and contacts 48 are closed for the same 110° rotation.

As long as the crank arms are 180° out of phase, the circuit, including the contacts 48, 30, 29, 47 and 41, the actuating coil 49 of the contactor 51 and contacts 44, is on open circuit all the time. Similarly, the circuit including contacts 48, 30, 29, 47 and 43, actuating coil 50 of contactor 52, and contacts 42 is on open all the time. The contacts 15 and 21 and the contacts 16 and 22 are thus closed and the two motors M1 and M2 will operate at full voltage and thus full speed.

If, as indicated in the figure, loom 1 is ahead of loom 2, say by 20°, as shown, then the time interval of energization of coil 49 is proportioned to the angle of lead. Contactor 51 thus opens the contacts 15 and 21 to insert the resistors 53 and 55 in the motor primary circuit. That the time interval of energization of coil 49 is proportional to the angle of lead will become more apparent from a study of the disposition of the cams in the figure. As cam 33 rotates in the direction indicated with the lead mentioned, contacts 47 will close and 20° later contacts 48 actuated by cam 34 close. Since both of the cams 33 and 34 actuate their respective limit switches 37 and 38 to closed position, the contacts 47 and 48 will be closed at the same time during 90° rotation. After contacts 47 are closed for 60°, contacts 41 are closed but at the same time, since shaft 4 lags by 200°, contacts 44 are still closed and will remain closed till shaft 4 moves through 20°. After the shaft 4 has turned through 20°, contacts 44 will open. This is the condition shown in the figure. The showing is thus exactly at the end of the correction cycle. An instant later contacts 15 and 21 close and both motors again operate on full voltage.

While contacts 42 close at the end of the correction cycle, contacts 47 open 10° ahead of the closure of contacts 43. The coil 50 can thus not be energized.

The resistors 53 and 55, as well as the corresponding resistors 54 and 56 for motor M2, are usually chosen to have an appreciable resistance value so that insertion of these resistors in the motor primary circuit will very materially reduce the motor torque during the short period the 75

contacts 15 and 21 are open. The resistors 53 and 55 and 54 and 56 may even be chosen to have infinite resistance value, that is, in some cases may not be used at all so that the operation of contactor 51 will open-circuit two motor armature leads for motor M1, and operation of contactor 52 will open-circuit two motor armature leads for motor M2.

If loom 2 leads loom 1, then an energizing circuit for coil 50 long enough to actuate contactor 52 is established. Contacts 16 and 22 are thus opened to insert the resistors 54 and 56 in the primary circuit of motor M2. Motor M2 is thus slowed down to bring the two looms again back to out-of-phase operation.

From the foregoing it is apparent that the length of time the leading motor torque is decreased will depend on the amount of out-of-phase operation. This is important because the 20 correcting effect is in proportion to the magnitude of the out-of-phase operation.

The relays 27 and 28 are a refinement not an absolute necessity. These relays prevent closing of the control circuits shown except when both 25 looms are in operation. These relays also permit unfailing starting of either motor when the other is at rest. For instance, if both looms should happen to be at rest in the particular position shown and contacts 29 and 30 were replaced by 30 solid leads then motor M1 could not be started.

During starting no attention need be paid to the relative positions of the crankshafts. Each motor is started independently. The motors drift along independently but as soon as they get within less than 60° of the out-of-phase operation for which the cams are adjusted, the system captures the control of the motors and thereafter the two motors operate their loads in the desired out-of-phase relation.

While I have described but one embodiment, I do not wish to be limited to the single embodiment but wish to be limited only by the scope of the claims hereto appended.

I claim as my invention:

1. In a system of control, in combination, a control circuit, a motor operating an unbalanced load, a second motor operating a similar unbalanced load, switching means operatively related with the output shaft of one motor for closing and opening contacts as a function of the angular position of the shaft, switching means operatively related with the output shaft of the other motor for closing and opening contacts as a function of the angular position of the second shaft, said switching means being so related to their respective output shafts that said control circuit is energized when the shafts are not out of phase, and means operable by the control circuit for opening the motor armature circuit of the motor that is leading by more than a selected out-of-phase value.

2. In a system of control, in combination, a motor driving a load of the type of a highly unbalanced flywheel, a second motor of about the same capacity as the first motor driving the same type of load at about the same speed, synchronizing means for so synchronizing said motors that when the unbalance force of one load is in one horizontal direction the unbalance force of the other load will be in the opposite horizontal direction, said synchronizing means comprising a control circuit, and switches in the circuit that synchronously close only in response to the direction of the unbalance forces that is other than 180° out of phase, and means responsive to the

energization of the control circuit for temporarily opening the motor armature circuit of the motor leading the other motor by more than the selected out-of-phase value.

3. In a system of control, in combination, a motor driving a load of the type of a highly unbalanced flywheel, a second motor of about the same capacity as the first motor driving the same type of load at about the same speed, synchronizing means for so synchronizing said motors that when the unbalance force of one load is in one horizontal direction the unbalance force of the other load will be in the opposite horizontal direction, said synchronizing means comprising a control circuit, and switches in the circuit that synchronously close only in response to the direction of the unbalance forces that is other than the selected out-of-phase value, means responsive to the energization of the control circuit for temporarily opening the motor armature circuit of the motor leading by more than the selected out-of-phase value, and means for controlling the interval the motor is deenergized as a function of the angle of lead.

4. In a system of control, in combination, a motor operating a relatively heavy reciprocating load back and forth in a horizontal direction, a similar motor operating a similar load back and forth in a horizontal direction that is parallel to the direction of operation of the load operated by the first motor, and means for briefly deenergizing the motor operating at a slightly higher speed at an instant when its load changes in direction from a direction that is opposite to the direction of movement of the load of the other motor to a direction that is the same as the direction of movement of the load of the other motor.

5. In a system of control, in combination, a motor operating a relatively heavy reciprocating load back and forth in a horizontal direction, a similar motor operating a similar load back and forth in a horizontal direction that is parallel to the direction of operation of the load operated by the first motor, means for briefly deenergizing the motor operating at a slightly higher speed at an instant when its load changes in direction

from a direction that is opposite to the direction of movement of the load of the other motor to a direction that is the same as the direction of movement of the load of the other motor, and means for controlling the period of deenergization as a function of the time period the loads move in the same direction.

6. In an industrial application where a large number of like motors separately operate an equal number of like relatively heavy reciprocating loads at about the same speed of means for operating the motors in pairs, preferably adjacent or aligned pairs, such that when one load of one motor moves in one horizontal direction the load of the other motor will move in an opposite horizontal direction in combination, a control circuit, switching means that close said circuit when one load has moved beyond its extreme position in one direction and is returning while the other load has not yet arrived at its opposite extreme position, and means for decreasing the energy supplied to the motor driving the leading load by the energization of the control circuit.

7. In an industrial application where a large number of like motors separately operate an equal number of like relatively heavy reciprocating loads at about the same speed of means for operating the motors in pairs, preferably adjacent or aligned pairs, such that when one load of one motor moves in one horizontal direction the load of the other motor will move in an opposite horizontal direction, in combination, a control circuit, switching means that close said circuit when one load has moved beyond its extreme position in one direction and is returning while the other load has not yet arrived at its opposite extreme position, means, operable by the energization of the control circuit, for decreasing the energy supply for a relatively short time interval of the motor driving the leading load, and means for controlling the length of said time interval as a function of the magnitude of the lead of the leading load.
